UNITED STATES PATENT OFFICE.

MARY HARDY CHANDLER, OF LAVONIA, GEORGIA.

GRATE ATTACHMENT.

1,245,087.

Specification of Letters Patent. Patented Oct. 30, 1917.

Application filed February 14, 1917. Serial No. 148,544.

To all whom it may concern:

Be it known that I, MARY H. CHANDLER, a citizen of the United States, residing at Lavonia, in the county of Franklin and State of Georgia, have invented certain new and useful Improvements in Grate Attachments; and I do hereby declare the following to be a full, clear, and exact description of the invention, such as will enable others skilled in the art to which it appertains to make and use the same.

This invention relates to grate attachments and more particularly to a novel form of means for adjustably securing and supporting a screen plate to the grate, whereby the screen plate may be readily raised and lowered for the purpose of removing ashes from under the grate and which will partially conceal the ashes under the grate when in a lowered position.

Another object of this invention is the provision of a pair of substantially U-shaped hangers adjustably secured to the grate for the purpose of slidably supporting the screen plate on the grate, thus permitting the screen plate to be raised and lowered with relation to the grate for the purpose of removing ashes from thereunder.

A further object of this invention is the provision of a means adjustably secured to the screen plate and adapted to engage the upper edge of the grate for supporting the screen plate in an elevated position.

A still further object of this invention is the provision of a grate attachment of the above stated character, which shall be simple, durable and efficient, and which may be manufactured and sold at a comparatively low cost.

With these and other objects in view as will become more apparent as the description proceeds, the invention consists of certain novel features of construction, combination and arrangement of parts as will be hereinafter more fully described and claimed.

For a complete understanding of my invention, reference will be had to the following description and accompanying drawing, in which:

Figure 1 is a front elevation of a grate attachment constructed in accordance with my invention,

Fig. 2 is a vertical sectional view of the same on the line 2—2 of Fig. 1,

Fig. 3 is a fragmentary detail sectional

view illustrating means for supporting the plate in a raised position.

Referring in detail to the drawing, the numeral 1 indicates a fire place having the usual hearth 2. A coal grate 3 having the usual slotted bottom 4 and the slotted front wall 5 is mounted in the fire place 1 at a point above the hearth 2 to form a space for receiving the ashes from the grate.

The foregoing description relates to a well known construction of grate and fire place and to which my invention is applied.

A pair of substantially U-shaped hangers 6 are adjustably secured to the front wall 5 of the grate 3 by bolts 7 and are adapted to extend downwardly from the grate to slidably receive a screen plate 8 adapted to partially close the front of the ash receiving space to prevent the ashes from falling outwardly into the room.

The upper ends of the hangers have countersunk slots 7' so as to slidably receive the heads of the bolts 7. A suitable hook 10 is formed on the plate 9, which is provided with slots 10' and which receive bolts 11 that extend through the slots of the plate 8 and are secured to a plate 12. The plates 9 and 12 are free to slide upwardly and downwardly on the plate 8 to permit the hook 10 to rest on the upper edge of the screen plate when not supporting the same. The slots 10' of the plate 9 permit of longitudinal adjustment of the hook 10 with relation to the screen plate, whereby the hook 10 may be kept at the center of the plate 8 so that the same will be evenly supported when in a raised position. When it is desired to remove the ashes, the hook 10 is raised upwardly by the ring 13, thus sliding the plates 9 and 12 upwardly until the bolts engage the top of the plate 8 and the hook 10 then engages the upper edge of the grate 3 and supports the screen plate in an elevated position, whereby the ashes may be readily removed.

From the foregoing description taken in connection with the accompanying drawing, it will be noted that a device is provided which will readily prevent ashes falling upon the hearth and scattering about or within the room.

While I have shown and described the preferred embodiment of my invention, it will be understood that minor changes in construction, combination and arrangement of parts may be made without departing

from the spirit and scope of the invention as claimed.

What is claimed is:

1. The combination with a fire place including a grate and a screen plate, of a pair of hangers adjustably secured to the grate and slidably supporting the screen plate for permitting said screen plate to be moved upwardly and downwardly with relation to the grate, and means for supporting the screen plate in an elevated position for permitting the ashes under the grate to be removed.
2. The combination with a fire place including a grate and a screen plate, of a pair of substantially U-shaped hangers adjustably secured to the grate and slidably receiving the screen plate for permitting the plate to be raised and lowered with relation to the grate, and means adjustably secured to the screen plate for supporting it in an elevated position.
3. The combination with a fire place including a grate having slots, and a screen plate, of a pair of substantially U-shaped

and relatively spaced hangers having slots therein, bolts extending through the slots of the grate and the slots of the hangers for adjustably securing said hangers to the grate, said hangers adapted to adjustably support the screen plate, and means adjustably secured to the screen plate for supporting it in an elevated position.

4. The combination with a fire place including a grate and a screen plate, of a pair of relatively spaced hangers adjustably secured upon each side of the grate, and plates secured to the screen plate and an arm formed on one of the last mentioned plates and having its free end bent to form a hook adapted to engage the upper edge of the grate for supporting the screen plate in an elevated position.

In testimony whereof I affix my signature in presence of two witnesses.

MRS. MARY HARDY CHANDLER.

Witnesses:

LOYD WELLBORN,
FRANK S. HARDY.
